FREDERICK W. TILTON, OF MOLINE, ILLINOIS.

Letters Patent No. 75,600, dated March 17, 1868; antedated March 7, 1868.

IMPROVEMENT IN SEED-PLANTING MACHINE.

The Schedule referred to in these Letters Patent and making part of the same.

TO ALL WHOM IT MAY CONCERN:

Be it known that I, FREDERICK W. TILTON, of Moline, in the county of Rock Island, in the State of Illinois, have invented certain new and useful Improvements in Seed-Planting Machines; and I do hereby declare that the following is a full and exact description thereof.

I will first describe what I consider the best means of carrying out my invention, and will afterwards designate what I believe to be new therein. The accompanying drawings form a part of this specification, and represent the novel features of my invention, with so much of the other parts as is necessary to show their relation thereto.

Figure 1 is a transverse section on the line X X, in fig. 2, showing the seed-cells and lower portion of the hopper of my improved seeding-machine.

Figure 2 is a plan view of both sections of the sleeve and seed-cells, and showing, in red lines, the hub of one of the carrying-wheels.

Figure 3 is a longitudinal section of the outer end of the axle, showing a portion of the adjusting-screw and nut that holds the wheel in position. This figure shows very clearly the arrangement of the screw-bolt which adjusts the size of the seed-cups.

Similar letters of reference indicate corresponding parts in all the figures.

A is a tubular shaft, of iron, which forms the axle of my machine, and on which the carrying-wheels are secured by means of cap-nuts B. A' is a shaft, of wood or metal, placed inside of the axle A, and adapted to be moved in a longitudinal direction relatively to the axle. C is a square-headed screw-bolt, which passes through the cap-nut B, and is tapped into the end of the shaft A'. The outer end of this bolt C is made square, as seen at c, and upon the part c is firmly secured a square head, c', by which the screw is operated. The bolt C is prevented from being moved endwise in either direction relatively to the nut B by means of the shoulder c² upon the inside, and the head c' upon the outside of the cap-nut B, and thus it will be seen that the shaft A' may be moved endwise in either direction relatively to the axle A, by turning the screw-bolt C, without depending on a spring to move it in either direction. D is a hoop or sleeve firmly secured by screws or otherwise upon the hollow axle A. E is a sleeve fitted loosely upon the axle A, and firmly secured to the enclosed part A' by means of screws I, which pass through longitudinal slots O in the axle A. The adjacent ends of the sleeves D and E are provided with long fingers d and e, and long notches d' and e', so arranged that the fingers d upon the sleeve D fit into notches e', of corresponding size, in the sleeve E, and the fingers e upon the sleeve E, fit into corresponding notches d' in the sleeve D. As the sleeve E is moved away from the sleeve D, spaces are left which serve as seed-cups for receiving and distributing the seed. The capacity of these cups may be increased or diminished to any desired extent by moving the loose sleeve E from or towards the fixed sleeve D, by means of the adjusting-screw C and the connecting-shaft A'. G is the lower part of a hopper, which receives the seed to be sown. Its under side is hollowed out so as to fit upon the upper cylindrical surface of the sleeves D E, with sufficient tightness to prevent the escape of seed. A flexible tongue or cut-off, g, of rubber, leather, or other flexible material, in the form of a sheet, is secured in the lower part of the hopper by means of a narrow sheet of metal, g¹, and compressing-screws g² tapped into the side of the hopper. As the axle revolves, the lower edge of this flexible cut-off g stands closely in contact with the cylindrical surface of the crowns D E, and prevents the seed from being crushed or injured between the lower side of the hopper and the edges of the seed-cups. H is a clutch firmly secured upon the axle A. K is a corresponding clutch, firmly secured to the inner end of the hub L of one of the carrying-wheels. When the carrying-wheel moves forward, the clutch K locks into the clutch H, and thus puts the sowing-apparatus into operation.

In moving from one field to another, or when, from any reason, it is desirable to move the machine forward without operating the sowing-apparatus, the clutch K is thrown out of contact with the clutch H, by means of a lever not represented, or any well-known device, which shall move the hub L outward toward the nut B, by taking hold in the groove K'.

Although I have shown and described but one set of sleeves, D E, it is evident that I may have any number of sleeves D secured upon the axle A, and any number of sleeves E secured to the shaft A', so that they can all be moved simultaneously by the adjustment of the single screw-bolt C.

My machine is capable of sowing in drills, or, by removing those parts which belong particularly to a drilling-machine and substituting therefor a deflecting-board for properly distributing the seed, can be used for broadcast sowing as well.

Having now fully described my invention, what I claim as new in seed-planting machines, and desire to secure by Letters Patent, is as follows:

I claim the adjusting-screw bolt C, having a recess or groove, c³, as represented, in combination with the section or crown D, fixed on the outer shaft A, and section or crown E, having an inward connection to the interior shaft A', all arranged substantially in the manner and for the purposes herein set forth.

In testimony whereof, I hereunto set my hand in presence of two subscribing witnesses.

FREDERICK W. TILTON.
